DESIGN FOR A PICTURE MOUNTING

Harry G. Koltnow, New York, N. Y., assignor to Kolto Art Products, Inc., New York, N. Y., a corporation of New York

Application January 18, 1947, Serial No. 136,231

Term of patent 14 years

(Cl. D29—20)

To all whom it may concern:

Be it known that I, Harry G. Koltnow, a citizen of Russia and a resident of New York, in the county and State of New York, have invented a new, original, and ornamental Design for a Picture Mounting, of which the following is a specification, reference being had to the accompanying drawing, forming part thereof, in which—

Fig. 1 is a perspective view of the picture mounting embodying my design.

Fig. 2 is a side view of the picture mounting embodying my design.

Fig. 3 is a front elevational view of the picture mounting embodying my design.

Fig. 4 is an end view thereof.

I claim:

The ornamental design for a picture mounting, as shown.

H. G. KOLTNOW.
